UNITED STATES PATENT OFFICE.

AUGUST CORTS, OF WYNCOTE, AND WARNER B. COOKE, OF JENKINTOWN, PENNSYLVANIA, ASSIGNORS TO WILLIAM WHARTON, JR., & COMPANY, INCORPORATED, OF PHILADELPHIA, PENNSYLVANIA, A CORPORATION OF PENNSYLVANIA.

SWITCH-STAND.

No. 831,834.

Specification of Letters Patent.

Patented Sept. 25, 1906.

Application filed November 11, 1905. Serial No. 286,942.

To all whom it may concern:

Be it known that we, AUGUST CORTS, residing at Wyncote, and WARNER B. COOKE, residing at Jenkintown, Pennsylvania, citizens 5 of the United States, have invented certain Improvements in Switch-Stands, of which the following is a specification.

The object of our invention is to construct a simple and effective switch-stand which 10 will lock a switch-rail in either the open or closed position and in which the connection with the switch-rail is made directly on the banner or target shaft.

In the accompanying drawings, Figure 1 is 15 a perspective view of our improved switch-stand with the cap removed. Fig. 2 is a plan view, partly in section, with the cap removed. Fig. 3 is a side view. Fig. 4 is a sectional view on the line 4 4, Fig. 2. Fig. 5 is a 20 detail perspective view showing the operating-lever in the mid-position to more clearly illustrate the connection between the operating-lever and the switch-lever or target-shaft. Fig. 6 is a detached perspective view 25 of the connecting-link, and Fig. 7 is a modified form of link.

A is the base of the stand having feet a, which rest upon the ties C C in the present instance, so as to provide a clear space be- 30 tween the ties for the switch-rod and the projecting portion of the switch-lever.

A' is a cap fitting upon the base A and inclosing the connecting mechanism. At one side of the base A is a bearing a' for the trun- 35 nion b of the operating-lever B. The bearing-cap a' forms part of the cap A', as clearly illustrated in Fig. 3. On the opposite end of the trunnion b is an arm b', bent at the angle shown, and this arm is perforated at b².

D is a vertical switch-lever shaft which 40 passes through the stand, having at its lower end an arm d and carrying at its upper end a target or banner D'. In the present instance the upper end of the shaft is squared, as 45 shown in Fig. 1, and the target is secured to one side of the shaft by bolts or other fastenings. A collar d' rests upon the cap A' and is fixed to the shaft by the confining-screw d², so as to hold the shaft D in the proper verti- 50 cal position.

The shaft D is slotted at d³ for the reception of a link E, Fig. 6. A pivot-pin e passes

through the heel of the link and through the shaft D, so that the link will freely swing in the slot of the shaft, but will prevent the 55 shaft turning independently of the arm. The outer end of the link is formed into a pin e', which fits in the opening b² in the arm b' of the operating-lever. Thus when the operating-lever is in the horizontal position, as 60 shown in Figs. 1 and 2, on either side the link E, bearing against arm b' and trunnion b at dead-center, locks the switch-lever shaft against rotary motion by any other means but the operation of the operating-lever. 65 By throwing the operating-lever through a half-circle from one horizontal position into the other the switch-lever shaft D is turned through one-quarter circle by the link E, bearing against the sides of the slot d³, swing- 70 ing at the same time on the center e and the rounded end e', moving in the opening b² of arm b. Thus the switch-rail is moved and the target turned to indicate the position of the switch. 75

f is an eyebolt secured to the arm d of the switch-lever. A switch-rod F is connected to this eyebolt by a pin f'.

B is the usual form of operating - lever and may or may not be provided with the 80 weight B'.

In Fig. 7 we have illustrated the link E' having a forked end which spans the target-shaft, dispensing with the slot in said shaft.

I are the usual stops or catches for the 85 operating-lever, preferably provided with the shoulder i', so that when the switch-lever is thrown into one position or the other it may rest upon the shoulders of a stop. The holes i are intended for the insertion of a pad- 90 lock.

It will be seen by the above description that the stand is made of very few parts, and the connection is so formed between the vertical switch-lever shaft and the operating-le- 95 ver that it will be impossible to accidentally shift the switch by any other means than the operating-lever, and yet the parts are so arranged that the operating-lever can be readily swung from one position to the other. The 100 operating-lever is moved through one-half circle. Thus it is locked on dead-centers in either position, while the switch and target-shaft is moved through one-quarter circle.

Thus the target can assume its two positions of danger and safety. Furthermore, as the target or banner is directly secured to the shaft of the switch-lever it is impossible to shift the switch-lever without turning the target or banner.

We claim—

1. The combination in a switch-stand of a casing, a vertical shaft having its bearings in the casing, an operating-lever having a trunnion mounted also in the casing arranged at right angles to the vertical shaft, an arm on said trunnion, a link pivoted to the said vertical shaft and coupled to the arm of the operating-lever, a target carried by the upper end of the vertical shaft, a crank at the lower end of the vertical shaft below the casing, a switch-rod coupled to the crank, substantially as described.
2. The combination in a switch-stand of a base, a cap mounted on the base, and inclosing the operating mechanism, a vertical shaft having its bearings in the base and in the cap, an arm on the lower end of the shaft under the base, a bolt secured to the arm, a switch-rod connected to the bolt, an operating-lever having a trunnion mounted in a bearing formed partly in the base and partly in the cap, an arm on said trunnion, and a link pivoted to the vertical shaft and coupled to the arm of the operating-lever, said arm and link being mounted within the casing formed by the base and cap, substantially as described.
3. The combination in a switch-stand of a base, a vertical switch-shaft extending through the base, an arm on the shaft under the base, a bolt secured to the arm, and a switch-rod coupled to the bolt, a target carried by the upper end of the vertical shaft, an operating-lever having a trunnion arranged at right angles to the vertical shaft and mounted in a bearing in the base, an arm on the trunnion bent and perforated at its outer end, a link pivoted to the vertical shaft and having a rounded end extending into the perforation of the arm, the parts being so arranged that the switch-shaft will be locked

against rotation when the operating-lever is in either of its two extreme positions, substantially as described.

4. The combination of a base, a cap mounted on the base, a vertical shaft extending through the base and through the cap, a collar resting on the cap and secured to the shaft holding the shaft in the proper vertical position, an arm on the end of the shaft below the base, a switch-rod connected to the arm, a target secured to the upper end of the shaft, an operating-lever having a horizontally-arranged trunnion mounted in a bearing in the base, the operating-lever being mounted on the outside of the base, an arm on the trunnion bent at its upper end and perforated, and a link pivoted to the vertical shaft, and having a portion extending into the opening in the arm whereby the vertical shaft will be locked against rotation when the operating-lever is in either of its two extreme positions, substantially as described.

5. The combination in a base, a cap mounted on the base, a vertical shaft extending through the cap and the base, a target secured to the upper end of the shaft, a switch-lever connected to the lower end of the shaft below the base, an operating-lever having a horizontal trunnion, an arm on the trunnion having a perforation at its outer end, the vertical shaft being secured, a link E in the form of a plate having a reduced portion in the form of a pin, the plate being pivotally mounted in the slot in the shaft, the reduced portion of the link extending into the opening in the arm of the operating-lever, the cap inclosing the link in the arm, substantially as described.

In testimony whereof we have signed our names to this specification in the presence of two subscribing witnesses.

AUGUST CORTS.
WARNER B. COOKE.
